United States Patent Office

Des. 179,770
Patented Feb. 26, 1957

179,770

CHAIR

Alfred C. Hoven, William S. Lindberg, and Walter E. Nordmark, Grand Rapids, Mich., assignors to American Seating Company, Grand Rapids, Mich., a corporation of New Jersey

Application February 23, 1956, Serial No. 40,285

Term of patent 14 years

(Cl. D15—1)

Fig. 5

This application is a continuation of our co-pending application Serial No. D. 36,084 filed May 18, 1955, now abandoned.

We claim:

The ornamental design for a chair, substantially as shown.
